(**) Term: **14 Years**

(21) Appl. No.: **29/332,478**

The ornamental design for alarm clock speaker system for media player, as shown and described.

(22) Filed: **Feb. 17, 2009**

DESCRIPTION

(51) **LOC (9) Cl.** **14-01**

FIG. 1 is a front, right side, perspective view of an alarm clock speaker system for media player showing my new design;

(52) **U.S. Cl.** **D14/168; D14/171; D10/2**

FIG. 2 is a front view thereof;

(58) **Field of Classification Search** D14/496,

FIG. 3 is a rear view thereof;

D14/498–511, 167–168, 188, 197–198, 169–172;

FIG. 4 is a right side view thereof;

360/99.02, 99.07; 369/75.11, 75.21, 77.11,

FIG. 5 is a left side view thereof;

369/77.21; 720/601, 612, 619, 649, 655;

FIG. 6 is a top view thereof;

455/344, 347–351; D10/2, 15

FIG. 7 is a bottom view thereof;

See application file for complete search history.

FIG. 8 is a cross section thereof on line 8—8 in FIG. 2; and,

(56) **References Cited**

FIG. 9 is a cross section thereof on line 9—9 in FIG. 6.
